Primary Examiner — Michael C Stout*Assistant Examiner* — Fitzgerald L Butac(74) *Attorney, Agent, or Firm* — Lawrence E. Thompson; The Thompson Law Office, P.C.(57) **CLAIM**

The ornamental design for a squared negative rake wood turning blade, as shown and described.

DESCRIPTION

FIG. 1 is a perspective view of a squared negative rake wood turning blade, in accordance with my new design;

FIG. 2 is a front side view thereof, with the rear, left, and right side views being mirror images thereof;

FIG. 3 is a top plan view thereof; and,

FIG. 4 is a bottom plan view thereof.

The broken lines show portions of a round negative rake wood turning blade which forms no part of the claimed design.
